UNITED STATES PATENT OFFICE.

ERNST JANTSCH, OF CINCINNATI, OHIO.

COMBINED ARMCHAIR AND BED.

1,346,206.

Specification of Letters Patent.

Patented July 13, 1920.

Application filed October 11, 1917. Serial No. 195,960.

To all whom it may concern:

Be it known that I, ERNST JANTSCH, a subject of the Emperor of Austria, residing at Cincinnati, in the county of Hamilton and State of Ohio, have invented certain new and useful Improvements in Combined Armchairs and Beds, of which the following is a specification.

It is the object of my invention to provide an arm-chair of novel construction arranged to be converted into a bed, and which is arranged to occupy little space when used as an arm-chair, the parts for forming the bed being arranged under and in connection with the seat and back and arms of the chair in novel manner, and the invention will be further readily understood from the following description and claims, and from the drawings, in which latter:

Figure 1 is a perspective view of my improved device in set-up relation as an arm-chair.

Fig. 2 is a perspective view of the seat and arm portions of the chair and the mattress portions of the bed in set-up relation as the same are located in the frame of the chair when set up as an arm-chair.

Fig. 3 is a perspective view of the frame of the chair, with the seat, arms, and mattress portions of the bed removed.

Fig. 4 is a central vertical section of my improved device in set-up relation taken on the line 4—4 of Fig. 1.

Fig. 5 is a detail in vertical section, taken on the line 5—5 of Fig. 4.

Fig. 6 is a cross-section of the arm-rest and back section of my improved device, taken on the line 6—6 of Fig. 7.

Fig. 7 is a central vertical section of my improved device, shown in set-up relation as a bed, the section being taken on a line corresponding to the line 4—4 of Fig. 1.

Fig. 8 is a central vertical section of my improved device, with the movable parts in intermediate relation, the section being taken on a line corresponding to the line 4—4 of Fig. 1; and,

Fig. 9 is a side elevation of the framework of the convertible section of my improved device, shown in intermediate relation similar to Fig. 8.

11 represents the frame-section of the arm-chair, and in the form shown, comprises sides 12, and a back 13, the sides being connected by a front strip 14.

At the respective sides of the frame-sec-

tion, at the inside rear portion thereof, runways 15 are located for the purpose to be presently described.

16 is a seat-section, the framework of which has sides 17 connected by a front strip 18 and a rear strip 19. The seat has a seat-cushion 21 at its normal upper side and a mattress 22 at its normal lower side, which latter becomes the upper side when the device is used as a bed.

The seat-section also comprises front finish-bars 61, preferably of wood, at the respective sides of said section. The normal front faces of the finish-bars are preferably of pleasing contour and form a finish for the front of the seat-section and the arm-portions, when the device is used as an arm-chair. The finish-bars comprise upward extensions 62, which extend above the normal level of the seat-surface and are received in front of the front ends of the arms of the arm-rest and back section 30, when the device is in set-up relation as an arm-chair. The finish-bars are provided with pintles 80 arranged to seat at the bottoms of grooves 24 in the inner faces of the sides 12 of the frame-section. These grooves may be covered by a plate 20. The seat-section 16 and the parts connected therewith swing 85 on these pintles when the device is being set up as a bed or being returned to set-up relation as an arm-chair.

25 is an end bed-section, forming a head bed-portion, which comprises sides 26 connected by cross-strips 27. Hinges 28 connect the sides 26 of the end bed-section with the sides 17 of the seat-section, at the normal front ends thereof, for hinging the end bed-section to the normal bottom of the seat, and so arranged that when the device is set up as an arm-chair, the end bed-section is received under the seat with its hinged end at the front of the chair, the end bed-section being received in rear of the front strip 14 100 of the frame-section.

When so arranged there is a space 63 between the bottom face of the end bed-section and the bottom 64 of the frame-section of the arm-chair, (see Figs. 4 and 5). This 105 space may be utilized for the reception of bedding or the like.

Rollers 29 are provided at the normal rear end of the end bed-section, these rollers coacting with the runways 15, which extend 110 preferably in curved form between the lower portion and upper end of the frame-section.

- When the seat is swung on its pivots for arranging the device in bed form, the rollers 29 will be thereby pushed rearwardly and upwardly along the runways upon shoulders 65, as shown in Fig. 7, so as to arrange the end bed-section in an upwardly slanting relation, with its rear edge on substantially a level with the top of the back 13 of the frame-section. The pockets act as retaining means for aiding in retaining the end bed-section in its assumed position.
- 30 is an arm-rest and back section, which comprises a framework consisting, for instance, of front uprights 53, upper side ledges 56 and lower side-pieces 33 rigidly secured respectively to the upper and lower ends of said front uprights at each side of said framework, a rear upright 34 rigidly secured to said side ledge and side-piece at each side of said section, a rear ledge 58 secured to each of said side ledges by a block 39, and a lower rear cross-piece 42 rigidly secured at its respective ends to said side-pieces 33. The rear portion of the arm-rest and back section has side-pieces 41 which normally extend up and down and are rigid parts of the framework of the section being fastened, for instance to the rear cross-piece 42 and the rear ledge 58.
- 30 The arm-rest and back section further comprise inner side-cushions 38, and an inner rear cushion 45, which are continued upwardly and outwardly in roll-form for forming outwardly extending arm-rests 36 and 37, extending outwardly above the upper edges of the sides 12 and back 13 of the frame-section, when the device is set up as an arm-chair. The downwardly extending sides and back of the arm-rest and back section are located inside the sides and back of the frame-section.
- The sides 41 are hinged at their normal lower ends to the normal rear ends of the sides 17 of the seat by means of hinges 43.
- 45 The normal rear-face of the back, which becomes the top face when in set-up relation as a bed, is provided with a mattress 44, which, when set up as a bed, becomes a continuation of the mattress 22. The normal upper end of this mattress has the back-cushion 45 at its other side, being the rear cushion of the arm portion of the chair, while the normal lower end of the mattress 44 is free to extend below the back-cushion 45 between the seat-section and the rear of the frame-section when in normal position.
- There is a gusset 46 between the normal lower end of the back-section and the normal rear end of the seat-section. Flexible 60 connections 47, for instance in the form of fabric straps, connect the seat-section and the arm-rest and back section for limiting the relative unfolding of the same, being secured at its ends to the cross-pieces 42 and 19.
- 65 The sides, back and arm-rests of the arm-

rest and back section are formed rigid with each other, the said section being hinged at its normal lower end to the normal rear ends of the sides of the seat. When the seat is swung on its pintles, the end bed-section 25 70 rides on the runways 15, as hereinbefore stated, and the seat is swung into vertical position, the arm-rest and back section being then drawn forwardly and placed in vertical position on the floor, whereby the mattresses 44 and 22 are brought into correlated horizontal positions so as to form the mattress of the bed in conjunction with the mattress 50 of the end bed-section. 75

The front ends of the sides of the arm-rest and back section of the chair, which become the lower ends of said section when set up as a bed, are provided with knobs 52, which serve as feet for said arm-rest and back section when the device is used as a 80 bed. These feet are arranged to be received in recesses 54 in the rear faces of the upward extensions 62 of the seat-section, when the device is in set-up relation as an arm-chair, the relations of the parts being clearly 85 shown by comparison of Figs. 4, 7, 8 and 9. The portions of the arm-rest and back section which find support on the floor, and are thereby liable to become marred, are hidden from view, when the device is set up as an 90 arm-chair, by having the upward extensions 62 of the finish-bars 61 received in front of the same.

When the sections are in normal relation as an arm-chair, the upper side ledges 56 1 and the rear ledge 58 of the arm-rest and back section are preferably supported on the tops of the sides 12 and back 13 of the frame-section. The rear end of the seat-section is preferably supported on shoulders 166, provided adjacent to the lower ends of the runways 15, and the rear end of the end bed-section is preferably independently supported, as by having the rollers 29 receive support on shoulders 67 at the lower ends 1 of said runways. The crushing of the cushion-parts, which are superposed when the device is set up as an arm-chair, is thus avoided.

The sides of the arm-rest and back section, the seat-section and end bed-section, when the device is in set-up relation as an arm-chair, are received within the sides and back of the frame-section, the front finish members or bars being received in front of 1 the front ends of the sides of the arm-rest and back section, forming a practical continuation of the contour of the front ends of the sides of the frame-section for presenting the finished appearance of an unconvertible 1 arm-chair.

Having thus fully described my invention, what I claim as new and desire to secure by Letters Patent, is:

1. In a combined arm-chair and bed, the 1

combination of a frame, a seat-section having pivot-connection therewith adjacent to the front end of said seat-section and provided with a seat-cushion at one face thereof, and a mattress at the other face thereof, and a back section provided with a back cushion at one face thereof and a mattress at the other face thereof, said back section comprising forwardly extending sides as rigid portions of said back-section, the front ends of said forwardly extending sides normally located adjacent to said pivot-connection, floor-supports at the normal front ends of said sides, the normal lower end of said back section and the normal rear end of said seat-section hinged together at their mattress-faces, said seat-section and back section arranged to be swung for positioning said mattresses in end-to-end relation with the normally forward end of said seat-section supported on said pivot-connection and with said sides of said back-section extending downwardly and supported on said floor-supports, and a tension-member between said hinged ends of said sections at their faces opposite their said mattress-faces forming supporting means for said hinged ends.

2. In a combined arm-chair and bed, the combination of a frame-section comprising two sides and a back forming three walls and having an opening at its front, and a convertible section movable in said opening, said convertible section comprising a seat-section having a seat-cushion at one face thereof and a mattress at the other face thereof; an arm-rest and back section comprising a back portion and forwardly extending side portions forming three walls received between said three walls of said frame-section, said arm-rest and back section hinged to one end of said seat-section and comprising inner cushioned walls at said three walls thereof extending above said seat-section, said forwardly extending side portions being rigid with said back portion, said second-named three walls provided with outwardly extending top-cushions normally extending outwardly over said first-named three walls of said frame-section and a mattress at the rear of said back-wall; and an end bed-section hinged to the other end of said seat-section, and provided with a mattress; said seat-section pivoted to the forward part of said frame-section and arranged to be reversed thereon, said forwardly extending side portions of said arm-rest and back section normally located with their forward ends adjacent to said pivot, and means whereby said arm-rest and back section and said end bed-section are caused to simultaneously move in opposite directions when said seat-section is

reversed for positioning their mattresses upwardly at the respective ends of said mattress of said seat-section, and with said rigid side portions extending downwardly from said mattress on said arm-rest and back section toward the floor, substantially as described.

3. In a combined arm-chair and bed, the combination of a frame-section comprising two sides and a back forming an inclosing wall having an opening at its front, and a convertible section comprising a seat-section pivoted to said frame-section at the normal front portion of said seat-section, said seat-section having a seat-cushion at one face thereof and a bed-surface at the other face thereof; an arm-rest and back section comprising upwardly extending sides and back provided with forward outward projections at their normally forward ends, which projections constitute floor-supports when the device is arranged as a bed, and a bed-surface at the rear of said back, said last-named section hinged at its normal lower rear end to the normal rear end of said seat-section; and an end bed-section normally received under said seat-section and comprising a bed-surface; said end bed-section and seat-section hinged together at their normal front ends, and said seat-section provided with parts received about said outward projections at the normally forward ends of said arm-rest and back section when said sections are in normal positions.

4. In a combined arm-chair and bed, the combination of a frame-section, and a convertible section, said convertible section comprising a seat-section provided with a seat-cushion at one face thereof and a mattress at the other face thereof, and an arm-rest and back-section comprising sides and a back normally extending above said seat-section and a mattress at the normal rear face thereof, the normal front ends of said sides comprising floor-supports, the normal lower end of said arm-rest and back section and the normal rear end of said seat-section hinged together, the normal front end of said seat-section being provided with upwardly extending finish-parts received in front of said floor-supports when said convertible section is in set-up relation as an arm-chair, and said mattresses arranged in end-to-end relation as a bed when said convertible section is in set-up relation as a bed.

In testimony whereof I have hereunto signed my name in the presence of two subscribing witnesses.

ERNST JANTSCH.
